PENDANT CROSS

Ennis Rickspoone, New York, N. Y.

Application May 14, 1952, Serial No. 19,788

Term of patent 14 years

(Cl. D45—16)

To all whom it may concern:

Be it known that I, Ennis Rickspoone, a citizen of the United States of America, residing in the Borough of Manhattan, city of New York, county of New York, and State of New York, have invented a new, original, and ornamental Design for a Pendant Cross, of which the following is a specification, reference being had to the accompanying drawing, forming part hereof.

Fig. 1 is a front elevational view; and

Fig. 2 is a side elevational view of the pendant cross.

The appearance of the rear of the pendant cross is substantially the same as the front as disclosed in Fig. 1 of the drawing.

The present application is a continuation-in-part of my application for design patent for a Pendant Cross, Serial No. D. 10,028, filed May 18, 1950, now abandoned.

I claim:

The ornamental design for a pendant cross, as shown and described.

ENNIS RICKSPOONE.
